APPARATUS FOR CENTRIFUGAL
SEPARATION

Dean H. Davis, Longmont, Colo.

Application July 25, 1949, Serial No. 106,613

17 Claims. (Cl. 233—15)

1

This invention relates to an apparatus for centrifugal separation of heavier and lighter particles, more particularly of mineral particles or the like, the heavier particles usually being valuable ore and the lighter particles usually being tailings or waste.

For the separation of heavier and lighter mineral particles, pulsating jigs or reciprocating screens have often been used. In such jigs or the like, pulp or a body of particles, normally consisting of a mixture of heavier and lighter particles is reciprocated at as fast a rate as possible to produce separation, due to the inertia of the larger particles and the consequent tendency for the lighter particles to move further at each pulsation or reciprocation. However, since not only the body of particles being separated, but also the entire apparatus must be reciprocated, jigs and reciprocating screens have normally consumed an undue amount of power. In addition, due to the limited rate of reciprocation, the separation efficiency has not been as high as desired.

Among the objects of the present invention are to provide a novel method of separating heavier and lighter particles, wherein centrifugal force is utilized; to provide such a method in which separation can be effectively accomplished and adequately controlled; to provide such a method which may be carried out in more than one manner; to provide apparatus particularly adapted to carry out the method of this invention; to provide such apparatus which involves a minimum of moving parts, and therefore requires a minimum of power; to provide such apparatus wherein the number of reciprocating parts is few, if any; to provide such apparatus which may be made in a number of different forms; and to provide such apparatus which is relatively low in initial and installation costs and economical in both operation and upkeep.

The present invention utilizes centrifugal force as the primary force producing separation, but in the method of this invention, the centrifugal force is periodically opposed by a rapidly pulsating force which apparently retards or prevents the movement of lighter particles with the centrifugal force to a greater extent than the heavier particles. The heavier particles are thus moved away from the lighter particles by centrifugal force, while the lighter particles are discharged along a different path. Normally, a liquid such as water is employed to carry the body of particles, both heavy and light, from one place to another, and in the method of this invention additional or auxiliary liquid is supplied, such

2

additional water being normally supplied to flow past the body of particles on the side in the direction in which the centrifugal force is acting and also is adapted to carry away the heavier particles. A rapidly pulsating force may be produced by periodically restricting or retarding the flow of auxiliary water, at a point slightly beyond the body of particles in the direction of flow of the auxiliary water, so that the water tends to reverse its flow, back toward the body of particles. Or, the pulsating force may be produced by the condensation of a vapor, such as steam, successive portions of which, when introduced into a body of water adjacent the body of particles and on the side of the direction in which centrifugal force is acting, will expand and then condense. Such intermittent expansion and condensation of steam may be made to take place relatively rapidly, producing an effect similar to that commonly known as steam or water hammer. Or, localized heating may be utilized to vaporize small portions of the liquid or water, which upon vaporization expand and are then condensed by the surrounding liquid or water, so that again a rapidly intermittent or periodic force, opposing the centrifugal force, is produced.

Apparatus particularly adapted to carry out the above method is illustrated in the accompanying drawings, in which:

30 Fig. 1 is a top plan view of a centrifugal separator constructed in accordance with the present invention;

Fig. 2 is a side elevation of the same, shown partly in section taken along offset line 2—2 of Fig. 1;

Fig. 3 is an enlarged horizontal section of a separating chamber or compartment of the apparatus of Figs. 1 and 2, taken along offset line 3—3 of Fig. 4;

40 Fig. 4 is a radial vertical section through the compartment, showing also certain associated parts including a valve which is opened and closed rapidly, the valve being in open position;

Fig. 5 is a view similar to Fig. 4, with the valve in closed position;

Fig. 6 is a further enlarged cross-section of the valve;

Fig. 7 is an arcuate vertical section, taken through the compartment along line 7—7 of Fig. 4;

Fig. 8 is a vertical section of a compartment similar to that of Figs. 3—7, but to which steam is supplied for producing a pulsating force;

Fig. 9 is a horizontal section taken through 55 several adjacent compartments or chambers of

a slightly different form of apparatus constructed in accordance with this invention, to which steam is also supplied;

Fig. 10 is a top plan view, partly in horizontal section, of the apparatus which includes the compartments of Fig. 9; and

Fig. 11 is a side elevation, partly broken away and partly in section to show the interior construction, of the apparatus of Fig. 10.

As illustrated in Figs. 1 and 2, apparatus constructed in accordance with this invention may include a plurality of compartments C, which are mounted for rotation on a main shaft S, a mixture of heavier and lighter particles or pulp being supplied to each compartment C through a feed pipe 10, which leads from a pulp feed launder 11, each of which rotate with the compartment C. Pulp is supplied to launder 11 from a stationary pipe 12, and the rotating assembly consisting of shaft S, compartments C and feed launder 11 is mounted centrally with respect to a tank T, the upper end of which is provided with a concentrate discharge launder 13 into which the heavier particles are discharged from pipes 14. From concentrate launder 13, an outlet pipe 15 conveys the concentrates to a sump 16, from which the concentrates may be moved to the next point of treatment, such as for further grinding, flotation or shipment or movement directly to a smelter or the like. The tailings or lighter particles are discharged from each compartment in a manner explained later, through tailings outlet 17 and fall into the tank T, the bottom 18 of which may slope to one side toward an outlet 19, as in Fig. 2, from which the tailings may be led to a settling pond or the like.

For rotating the central assembly, shaft S is provided at its lower end with a pulley 20, engaged by a belt 21, or shaft S may be driven in any other suitable manner, such as by a direct motor drive, while a suitable bearing 22 is also preferably provided at the lower end of the shaft. Shaft S is hollow to provide a passage 24 for auxiliary water from a supply pipe 25, led through the shaft to a series of distributing pipes 26, one for each compartment C, a suitable rotatable sealing connection, preferably of a conventional nature and therefore not shown, being provided at the lower end of the shaft S, to connect the pipe 25 and passage 24 in shaft S. An upper shaft 27 is also hollow, for passage therethrough of a pulsation control shaft 28, provided at its upper end with a double grooved pulley 29, each groove being engaged by a belt 30, there preferably being two belts extending in diametrically opposite directions, to balance the thrust from the belts and thereby tend to maintain the rotating parts in alignment about the axis of rotation.

Each distributing pipe 26 extends outwardly and then upwardly past the corresponding compartment C to a pulsating device, such as a valve V, while the launder 11 and compartments C may be supported from the shaft S in any suitable manner, such as partly by pipes 26 and also by suitable structural elements, such as rings 31 and brackets 32. A suitable bearing for upper shaft 27 may be provided, if desired. The shaft S and the compartments C along with it, are rotated at a suitable speed to produce the desired centrifugal force, such as at about 750 R. P. M., while the pulsation control shaft 28 is driven at a considerably higher speed, such as at about 3,000 R. P. M. to produce rapid opening and closing movements of valves V, as explained below.

Referring now to Figs. 3-7, each compart-

ment C may comprise an inlet chamber 34 and an outlet chamber 35, separated by a screen 36, having a mesh of a suitable size in accordance with the size of the particles being separated. The inlet chamber 34 may be formed by a box-like structure having an arcuate rear wall 31, top and bottom walls 38 and 39, respectively, side walls 40 and limited front walls 41 and 42, along the latter of which tailings outlet 17 extends vertically, to permit adequate discharge of the lighter particles. Screen 36 is mounted in the space between the front walls 41 and 42, while vertically disposed, inwardly extending flanges 43 and 44 are disposed at the opposite sides of the screen. The outlet chamber 35 may be substantially pyramidal in shape, formed by triangular top and bottom walls 45 and side walls 46, which converge to an outlet opening 47, to which distributing pipe 26 is connected, as by a nipple 48.

As in Fig. 3, the pulp from feed pipe 10, which enters the inlet chamber 34 at one side and at an upper position, as in Fig. 4, due to centrifugal force created by rotation, builds up along the front wall 41 until it overflows flange 43 and then forms an arcuate bed 49 of material or mineral particles to be separated, which will rest on screen 36, the thickness of the bed 49 being determined by the height of flanges 43 and 44. During operation, of course, the bed 49 of material will be maintained on screen 36 between the flanges. Centrifugal force will, of course, tend to throw the material against the outer wall of the compartment and the screen 36, tending to maintain the bed from top to bottom, against the force of gravity. The outlet chamber 35 will normally be filled with water, as from the distributing pipe 26, or primarily water introduced with the pulp through feed pipe 10, the normal flow of the auxiliary water, as in Fig. 4, being upwardly in distributing pipe 26 past outlet 41, through valve V and thence through pipe 14 into the concentrate launder.

The pulsations or periodic forces opposing centrifugal force are produced by the pulsating device, in this instance by the rapid opening and closing of valve V, which upon closing, as in Fig. 5, will temporarily restrict the normal flow of water and cause the water to tend to back up through the opening 41 into the chamber 35. As indicated previously, the pulsation control shaft 28 is rotated at a relatively high speed, such as 3,000 R. P. M., so that the opening and closing of the valve V will be on the order of 3,000 times per minute, less the speed of rotation of the shaft S, which if at 750 R. P. M. will mean that each valve V will open and close about 2250 times per minute. Thus, there will actually be insufficient time for water to flow from the valve V back to the opening 41, but rather the water will be in a constant state of agitation, particularly on the discharge side of screen 36, i. e. the water will tend to flow first one way and then the other. When the tendency toward flow is against screen 36, the water will push the lighter particles back from the screen, since the lighter particles will be carried more readily by the counterforce of the water than will the heavier particles. As a result, the layer of material next to the screen will soon be composed of heavier particles, which during the tendency of the water to flow away from the screen 36, will be carried by centrifugal force through the screen, and then be carried along with the water through the outlet 41 and thence 75 through valve V and into the discharge launder.

The lighter particles will move along in the bed 49 toward the flange 44, over which they will flow to the tailings outlet 17 which preferably extends from top to bottom of front wall 39, as indicated previously, to facilitate the discharge of the lighter particles. Of course, the concentration of heavier particles in the bed will decrease from the entrance flange 43 to the exit flange 44.

As in Figs. 4 and 5, the pulsation control shaft 28 may be provided at its lower end with a crank throw 50 and a crank pin 51, which is rotatable in a block 52 to which a series of rods 53, one for each valve V, are attached. Each valve V may be actuated by a valve rod 54, which reciprocates within a sleeve 55, which passes through a supporting and guide tube 56. As in Fig. 6, the sleeve 55 may also carry at its outer end a cone 57, adapted to engage an annular valve seat 58, formed at the outlet of the valve V, cone 57 preferably being made of or provided with a layer of soft material, so that it can close effectively on mineral particles, which will normally be carried by the water flowing through the valve. Valve rod 54 preferably makes a lost motion connection with the sleeve 55, as by locking nuts 59 mounted on the outer end of the valve rod 54, so that the valve will not open immediately after closing, but there will be a slight period of rest when the valve closes. Thus, as the valve rod moves outwardly, the pressure of water within the valve V will force the cone 57 against seat 58, but the valve rod will travel slightly further, such as to the position of Figs. 5 and 6. Also, when the valve rod begins to move rearwardly, the valve will remain closed until the nuts 59 engage the end of sleeve 55. The valve will, of course, remain open and will not begin to close until the crank pin 51 reaches its extreme position, away from the particular valve V, such as shown in Fig. 4. Preferably, the position of nuts 59 on valve rod 54 is adjusted so that the valve will remain closed for about as long as it remains open. Of course, this time will be relatively small, since if the valve openings occur on the order of 2250 times per minute, only a fraction of a second is consumed during each opening and closing. However, these rapid pulsations introduced into the auxiliary water, and which periodically produce forces opposing the centrifugal force within each compartment C, permit the heavier particles to pass through the screen and tend to keep the lighter particles back from the screen, so that as the bed of material moves across the screen, more and more of the heavier particles will pass through the screen, while the lighter particles will finally be discharged over the flange 44 and into the tailings outlet 17, as indicated previously.

Any desired number of compartments C may be utilized, since the four compartments shown in Fig. 1 are illustrative only. Also, any other suitable manner of actuating the valve V, and in fact any other suitable type of valve or means for intermittently or periodically restricting the flow of the auxiliary water, may be utilized. As indicated previously, instead of utilizing a valve or other means as the pulsating device for periodically restricting the flow of the auxiliary water, the pulsating device may introduce vapor into the outlet chamber and the periodic condensation of the vapor utilized to produce the desired pulsations.

A suitable modification adapted to carry out such vapor condensation is illustrated in Fig. 8, in which a steam supply tube 62 passes centrally down an upper shaft 27' to a steam distributing

block 63, the upper end of tube 62 being provided with a suitable rotating seal, conventional in nature and therefore not shown. A series of steam distributing pipes 64, one for each compartment, 5 lead from the block 63 to each outlet chamber 35' and comprises the pulsating devices. Steam may be introduced continuously into the water therein, since as steam enters from the distributing pipe 64, it will expand to produce a force tending to oppose the centrifugal force produced by the rotation of the compartment C', but will immediately be condensed, this expansion and condensation being repeated rapidly. The pressure and temperature of the steam is preferably correlated with the conditions within the chamber 35', so that the expansions and condensations, with resultant pulsations, will take place sufficiently rapidly to produce periodic forces opposing centrifugal force at a sufficiently rapid rate to cause effective separation of the heavier and lighter particles.

The compartment C' of Fig. 8 is similar to the compartment C of the previous embodiment, except that the outlet chamber 35' is preferably made slightly larger, to accommodate steam introduction, as by the triangular top and bottom walls 45' and side walls 46' being longer. Also, the auxiliary water distributing pipes 26' are similar to the pipes 26 of Fig. 2, in extending outwardly and then upwardly past the outlets 47 of the compartments, at which point each is connected with the outlet 47 by a nipple 48'. However, the upper end of each distributing pipe 26' does not lead to a valve, but rather merely terminates in a laundry discharge section 65 which is preferably provided with a restricted outlet 66 tending to restrict the flow of auxiliary water and insure that the chamber 35' will be full of water.

40 In the steam introduction embodiment of Figs. 9-11, the compartments may have inlet chambers which are combined into a single annular inlet chamber. Thus, a single casting may be made to produce a series of outlet chambers 70, similar to chambers 35 of compartments C in having converging, triangular top and bottom walls 71 and side walls 72, a screen 36' being individually mounted, as shown, between posts 73 which separate the chambers. If desired, a single screen, 45 extending around the inner periphery of the casting, may be attached, as by spot welding or the like, to each of the posts 73 and also to the upper rim 74 and bottom 75 of the casting, as will be evident from Fig. 11. As in Fig. 9, a pair 50 of adjacent chambers 70 are supplied with steam from a steam distributing pipe 76 having a pair of branches 77, one of which connects with each 55 of the chambers.

As in Figs. 10 and 11, the flow of material 60 along the screens 36' is from bottom to top, the feed thereto being beneath the outer edge of a distributing cone 78, through the apex of which extends the mouth of a stationary pulp feed pipe 12', the pulp flowing beneath the cone 78 and substantially equally to the lower portion of each 65 screen 36'. The heavier particles, as before, pass through the screen, while the lighter particles are moved upwardly and over the rim 74, after which they are thrown by centrifugal force into the tank T to be discharged through the tailings outlet 19. A steam and water distributor 79 may be made integral with the bottom 75 of the compartment casting, or may be made separately or by separate parts, such as plates and circumferentially apertured rings, and attached to the

compartment casting and to shaft S', which as before, is hollow to provide a passage 24' for water supplied by auxiliary water supply pipe 25. Also, as before, the shaft S' may be provided with a pulley 20 driven by a belt 21, and a bearing 22 may also be provided. The steam and water distributor 79 may be provided with a lower water chamber 80, which connects with the water passage 24' in shaft S', and with an upper steam chamber 81, to which a centrally disposed steam supply pipe 82 leads from above, the latter being connected by a conventional rotary sealing connection 83 with a stationary steam supply pipe 84. Steam pipe 82 preferably extends through pulp feed pipe 12' and also centrally through cone 18 down to steam chamber 81. Both water chamber 80 and steam chamber 81 are provided with a number of outlets, the number of water outlets corresponding to the number of chambers, and the number of steam outlets, corresponding to one-half the number of chambers, since each steam distributing pipe 76 supplies two chambers, as indicated previously. Each water distributing pipe 85 may extend outwardly and then upwardly to a T 86 connected to the outlet 47' of the corresponding chamber 70, while a discharge pipe 87, provided with a goose neck at the top for discharge of the auxiliary water and concentrates into the concentrate launder 43, extends upwardly from T 86.

During operation of the apparatus of Figs. 9-11, the shaft S may be rotated at a suitable speed, such as 750 R. P. M. as before, while the pulp is fed beneath cone 78 to the screens 36'. Centrifugal force will cause a bed of mineral particles to build up on the screen, while each chamber 70 will be filled with water, including water thrown outwardly through the screen from the incoming pulp, as well as water from distributing pipe 85. The auxiliary water will flow continuously into the concentrate launder, but steam introduced into each chamber 70 will periodically expand, producing a force opposing centrifugal force, and then condense. As before, centrifugal force will move the heavier particles through the screen, but the lighter particles will be prevented from moving through the screen by the periodic steam expansions. As indicated previously, the pulsations or intermittent forces produced by the steam are quite rapid in succession, so that the water in each chamber 70 is in a state of constant agitation, i. e. tendency to flow back through the screen and then through the outlet 47'. Also, the bed behind each screen 36' will build up until it overflows the upper rim 74, whereupon the lighter particles will be discharged outwardly into the tank T for ultimate discharge through tailings outlet 19.

From the foregoing, it will be apparent that the method and apparatus of this invention fulfil to a marked degree the requirements and objects hereinbefore set forth. The production of a rapidly pulsating force, tending to oppose centrifugal force, particularly when produced in a liquid adjacent the point of separation between the heavier and lighter particles, tends to insure that the separation will not only be effective, but also readily controlled. The utilization of an auxiliary stream of liquid, which tends to flow past the point of separation and which carries with it the heavier particles separated, simplifies the problem of disposition of such heavier particles. The periodic obstruction of the normal flow of such liquid, preferably at a point closely adjacent but beyond the point of connection, insures

that the pulsating forces will be transmitted directly to the bed of particles being separated without loss of effectiveness. (It can be seen that if rapid pulsations are attempted to be introduced into the auxiliary stream of liquid prior to the outlet 47, such as in the supply pipe 25, the pulsations will tend to merge and lose effectiveness during flow through the pipes. In addition, the pulsations cannot be made as positive by attempting to alternate the flow prior to the compartments, unless unduly high pressures are utilized, since the opening of a valve, to provide a sudden rush or pulse of water, normally cannot be made as positive as a stoppage of flow due to the sudden closing of a valve. In this connection, it is to be noted that "water hammer," in household pipes, invariably takes place in the line ahead of the valve or restriction producing it, and not after.)

The alternative method of this invention, wherein a vapor, such as steam, is periodically condensed within a body of liquid disposed radially outwardly from the separating bed of particles, is both easy to apply and economical to use. Also, steam may be supplied at a constant pressure, since the natural tendency for successive portions of the steam to expand and condense within such body of liquid, is taken advantage of in a novel and effective manner.

The apparatus adapted to carry out the above invention involves primarily only rotating parts, which require a minimum of power, after being brought up to speed. When valves are utilized to obstruct the flow of auxiliary liquid, the reciprocating parts are few in number and light in weight, so that little additional power is required. When steam is supplied to the outlet chambers, there are no reciprocating parts necessary, so that additionally less motive power is utilized. The absence of heavy reciprocating parts also reduces the initial cost of bearings, driving parts and the like; reduces installation costs of heavy foundations and the like; and also reduces maintenance costs, as well as eliminating vibration problems in adjacent or connected equipment or structures.

While various manners in which the method of this invention may be carried out, and several forms and variations of the apparatus are described, it will be understood that other changes may be made therein, and that other forms and manners of carrying out the method may exist, all without departing from the spirit and scope of this invention.

What is claimed is:

1. Apparatus for separating heavier and lighter particles carried by liquid in a pulp, which comprises a series of circumferentially spaced compartments, each including an outlet chamber having a radially outwardly spaced outlet and a foraminous wall on the radially inward side of said chambers; means for rotating said compartments about a central axis; means for supplying pulp to the inner side of each of said foraminous wall; auxiliary water-supply means having a connection with each said outlet and adapted to supply auxiliary liquid to flow past said outlet and to a point of discharge, such auxiliary liquid being adapted to carry with it heavier particles passing through said foraminous wall and then to said outlet; and means for introducing a condensable vapor into each said chamber.

2. Apparatus for separating heavier and lighter particles of mineral and the like, which comprises a compartment rotatable about an axis substan-

tially perpendicular thereto and having a screen extending across the same, a pulp inlet and a lighter particle outlet on the inner side of said screen, and a heavier particle outlet on the outer side of said screen; means for rotating said compartment about said axis; means for supplying pulp to said pulp inlet; means connected with said heavier particle outlet for supplying auxiliary water to said outlet, and conveying water and heavier particles from said outlet to a point of discharge; and a pulsating device located at a point between said heavier particle outlet and said point of discharge for periodically impeding the flow of water and heavier particles from said outlet.

3. Apparatus for separating heavier and lighter particles of mineral and the like, as defined in claim 2, wherein said means for supplying auxiliary water to said heavier particle outlet and conveying water from said outlet comprises a pipe, and said pulsating device for periodically impeding the flow of water and heavier particles from said outlet comprises a valve and means for opening and closing said valve rapidly.

4. Apparatus for separating heavier and lighter particles of mineral and the like, as defined in claim 3, wherein said valve closes in the direction of flow of water and heavier particles from said outlet.

5. Apparatus for separating heavier and lighter particles of mineral and the like, which comprises a compartment rotatable about an axis substantially perpendicular thereto and having a screen extending across the same, a pulp inlet and a lighter particle outlet on the inner side of said screen, and a heavier particle outlet on the outer side of said screen; means for rotating said compartment about said axis; means for supplying pulp to said pulp inlet; means connected with said heavier particle outlet for supplying auxiliary water to said outlet, and conveying water and heavier particles from said outlet to a point of discharge, the flow of auxiliary water in said means being substantially uninterrupted up to said heavier particle outlet; and a pulsating device located at a point in the path of flow of heavier particles between said screen and the point of discharge of said auxiliary water and heavier particles, for producing periodic pulsations in the flow of water through said compartment, which pulsations periodically oppose the centrifugal force produced by rotation of said compartment.

6. Apparatus for separating heavier and lighter particles carried by liquid in a pulp, which comprises a series of circumferentially spaced compartments, each including an outlet chamber having a radially outwardly spaced outlet and a foraminous wall on the radially inward side of said chamber; means for rotating said compartments about a central axis; means for supplying pulp to the inner side of each said foraminous wall; auxiliary water supply means having a connection with each said outlet and adapted to supply auxiliary liquid to flow past said outlet and to a point of discharge, such auxiliary liquid being adapted to carry with it heavier particles passing through said foraminous wall and then to said outlet; and means for periodically impeding the flow of said auxiliary liquid and the particles carried with it at a point in the direction of flow thereof beyond said outlet connection, to produce a pulsating force in said chamber periodically opposing the centrifugal force produced by rotation of said compartments.

7. Apparatus for separating heavier and lighter particles as defined in claim 6, including a valve in each said supply means between said chamber outlet and said point of discharge; and means for periodically opening and closing said valves.

8. Apparatus for separating heavier and lighter particles as defined in claim 1, wherein such liquid comprises water, and including means for introducing steam into each said chamber.

9. In apparatus for separating heavier and lighter particles, a compartment having inlet and outlet chambers; said inlet chambers having an arcuate rear wall, end, top and bottom walls, and front walls of limited extent providing an opening therebetween, a screen extending across said opening, an inwardly extending flange disposed vertically at each side of said screen, a pulp inlet extending through said rear wall opposite the upper portion of one said front wall, and a tailings outlet extending vertically along the opposite front wall; said outlet chamber having outwardly converging walls extending from said inlet chamber to an outlet opening for heavier particles; an auxiliary water supply pipe extending upwardly past and having a connection with said outlet opening; means for supplying water to said auxiliary pipe at a point below said connection; a valve in said pipe above said connection; means for rotating said compartment and pipe; and means for periodically opening and closing said valve.

10. Apparatus for separating heavier and lighter particles, which comprises a series of circumferentially spaced compartments, each including an outlet chamber having a radially outwardly spaced outlet and a foraminous wall on the radially inward side of said chamber; means for rotating said compartments about a central axis; means for supplying pulp to the inner side of each said foraminous wall; a series of auxiliary water pipes, each having a connection with one of said outlets and adapted to supply a liquid to flow past said outlet and to a point of discharge and to carry with it heavier particles passing through said foraminous wall and to said outlet; valves in said pipes beyond said connections in the direction of flow of liquid in said auxiliary pipes; a cylindrical tank enclosing said compartments and adapted to receive lighter particles discharged from said compartments; a launder extending around the upper edge of said tank for receiving said discharged auxiliary water; means for rotating said compartments; and means for periodically opening and closing said valves.

11. Apparatus for separating heavier and lighter particles, which comprises a series of circumferentially spaced chambers each having walls converging to an outwardly spaced outlet from a foraminous wall on the radially inward side of said chamber; means for rotating said chambers about a central axis; means for supplying pulp to the inner side of each said foraminous wall; a series of auxiliary water pipes connecting to said outlets and adapted to supply a liquid to flow past said outlets and to a point of discharge and to carry with it heavier particles passing through said foraminous wall and to said outlet; and a series of steam distributing pipes, each extending to a point between two adjacent chambers and having a branch leading to each such chamber.

12. Apparatus for separating heavier and lighter particles, comprising a series of circum-

11

ferentially spaced compartments having inlet and outlet chambers; said inlet chambers having an arcuate rear wall, end, top and bottom walls, and front walls of limited extent providing an opening therebetween, a screen extending across said opening, an inwardly extending flange disposed vertically at each side of said screen, a pulp inlet extending through said rear wall opposite the upper portion of one said front wall, and a tailings outlet extending vertically along the opposite front wall; said outlet chamber having outwardly converging walls extending from said screen to an outlet opening; a lower shaft for supporting said compartments and having a driving attachment, said lower shaft having a water passage therein; an auxiliary water supply pipe connecting with said lower shaft passage; a series of auxiliary water distributing pipes, each extending from said shaft and upwardly past and having a connection with one of said outlet openings; an upper shaft providing a journal for a pulsation control shaft; a double pulley on the upper end of said pulsation control shaft; a pair of diametrically opposed belts engaging said pulley in balancing relation; a crank pin at the lower end of said pulsation shaft; a valve in each said auxiliary pipe at a point above said connection with said outlet opening, each said auxiliary pipe extending radially outwardly from said valve; a valve rod for each valve connected with said crank pin, each said valve rod having a lost-motion connection with said valve; a generally cylindrical tank enclosing said compartments, said tank having a bottom sloping to a tailings outlet at one side for drainage of tailings received by said tank from said tailings outlets of said compartments; and a launder extending around the upper edge of said tank for receiving water and concentrates discharged from said auxiliary pipes.

13. Apparatus for separating heavier and lighter particles, which comprises a generally cylindrical casting having a flat bottom, an outwardly spaced, inwardly extending upper rim, and a series of circumferentially spaced outlet chambers each having a radially outwardly spaced outlet, each said outlet having outwardly converging walls and said casting forming upright posts between said outlet chambers, which posts extend from said casting bottom to said rim; a screen extending between said posts across the opening to each said outlet chamber; a lower shaft for supporting said casting and having a driving attachment, said lower shaft having a water passage therein, an auxiliary water supply pipe connecting with said lower shaft passage; means forming a water distributor and a steam distributor at the upper end of said lower shaft, said water distributor connecting with said lower shaft passage; a series of auxiliary water pipes extending from said water distributor and upwardly to connect to said outlets, said auxiliary pipes extending upwardly past said outlets and then outwardly to a point of restricted discharge; a pulp inlet pipe extending to a central point over the bottom of said casting; an inverted cone through the apex of which said inlet pipe passes and having its lower edge spaced slightly above said casting bottom and adjacent said screens; a steam inlet pipe extending centrally through said pulp inlet pipe and cone and casting bottom to said steam distributor; a series of steam distributing pipes extending from said steam distributor outwardly and then upwardly to a point between alternate outlet chambers;

12

a branch steam pipe leading from each steam distributing pipe to the two adjacent outlet chambers to connect with the interior thereof; a cylindrical tank enclosing said casting and adapted to receive lighter particles discharged over said rim; and a launder extending around the upper edge of said tank for receiving the discharge from said auxiliary pipes.

14. In apparatus for separating heavier and lighter particles, a compartment having inlet and outlet chambers; said inlet chambers having an arcuate rear wall, end, top and bottom walls, and front walls of limited extent providing an opening therebetween, a screen extending across said opening, an inwardly extending flange disposed vertically at each side of said screen, a pulp inlet extending through said rear wall opposite the upper portion of one said front wall, and a tailings outlet extending vertically along the opposite front wall; said outlet chamber having outwardly converging walls extending from said inlet chamber to an outlet opening; an auxiliary water supply pipe extending upwardly past and connecting with said outlet opening; and a steam pipe extending into said outlet chamber.

15. In apparatus for separating heavier and lighter particles, a compartment having inlet and outlet chambers; said inlet chambers having an arcuate rear wall, end, top and bottom walls, and front walls of limited extent providing an opening therebetween, a screen extending across said opening, an inwardly extending flange disposed vertically at each side of said screen, a pulp inlet extending through said rear wall opposite the upper portion of one said front wall, and a tailings outlet extending vertically along the opposite front wall; said outlet chamber having outwardly converging walls extending from said inlet chamber to an outlet opening; an auxiliary water supply pipe extending upwardly past and connecting with said outlet opening; and a steam pipe extending into said outlet chamber.

16. Apparatus for separating heavier and lighter particles of mineral and the like, which comprises a compartment having a foraminous screen extending across the same; means for rotating said compartment to subject material therein to centrifugal force; means for supplying a pulp including a liquid carrying heavier and lighter particles to said compartment at a point inwardly of said screen; means for removing lighter particles from a point in said compartment inwardly of said screen, said compartment having an outlet for heavier particles outwardly of said screen; means for supplying a stream of auxiliary liquid normally flowing past said compartment and communicating with said compartment at said heavier particle outlet; and a pulsating device located in the path of flow of said auxiliary liquid at a point in the direction of flow thereof beyond said heavier particle outlet, for periodically impeding the flow of such auxiliary liquid to produce a pulsating force which opposes such centrifugal force periodically.

17. Apparatus for separating heavier and lighter particles of mineral and the like, which comprises a compartment having a foraminous screen extending across the same; means for rotating said compartment to subject material therein to centrifugal force; means for supplying a pulp including a liquid carrying heavier and lighter particles to said compartment at a point inwardly of said screen; means for removing

lighter particles from a point in said compartment inwardly of said screen, said compartment having an outlet for heavier particles outwardly of said screen; means for supplying a stream of auxiliary liquid normally flowing past said compartment and communicating with said compartment at said heavier particle outlet; and means for introducing steam into said compartment at a point outwardly of said screen, to produce a pulsating force opposing such centrifugal force 10 by periodic steam condensation.

DEAN H. DAVIS.
